FISH LURE

Earl M. Scanlan, Denver, Colo.

Application August 19, 1957, Serial No. 47,441

Term of patent 7 years

(Cl. D31—4)

Fig. 1

Fig. 2

Fig. 3

The bottom, or underface, of the lure is substantially plain.

I claim:

The ornamental design for a fish lure, substantially as shown and described.
